STENCIL INKING MACHINE

Albert W. Mills and Frank J. Furman, Endicott,
N. Y., assignors to International Business Ma-
chines Corporation, New York, N. Y., a corpo-
ration of New York

Application May 12, 1942, Serial No. 442,643

5 Claims. (Cl. 101—124)

This invention relates to stencil printing and inking machines and particularly to the type which utilizes stencil cards indented by the typewriter and which stencils are usually in the form of a card with a strip of Yoshino paper across the window of the card.

The main object of the present invention is to provide a machine which is simple in its construction and operation but will possess dual functions; namely, the capability of inking stencils to be used in a stencil addressing machine for the first time and at the same time printing on an adjacent record card from the inked stencils to provide a file card.

It is explained that printing from the inked stencils by a stencil addressing machine is done more efficiently for the first time by preconditioning or preinking the stencils before they are passed through the addressing machine. After the stencils have been "cut" by a typewriter they are manually inserted in the present machine and by motor driven inking mechanism of an improved form the stencils are evenly inked and to the predetermined degree. The passage of such conditioned stencils through the customary addressing machine will enable better imprints to be made.

A subordinate function enables the printing from the inked stencils upon the file cards which are placed adjacent the stencils to be inked so that there will be provided a card file of each of the stencils prepared since it is easier to read the printed matter on a card than reading the matter indented on the stencil by the typewriter.

Another object of the invention is the provision of a simple portable motor operated stencil inking and printing machine that will ink and print from inked stencils which are individually inserted in the machine and by the manipulation of a motor release bar the machine will be set in operation to perform its function. In this manner the stencils are individually conditioned at the will of the operator.

A still further object of the invention is to provide an improved form of inking arrangement which will insure even distribution of the ink over the inking rollers and finally the proper even distribution of the ink on the stencils, enabling them to be conditioned in the proper manner.

A more specific object of the invention is to provide means which will vary the extent of ink transferred to the inking roller and which adjustable means is under control of the operator so that the efficient inking operations can be insured.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the improved stencil printing machine.

Fig. 2 is a longitudinal sectional view taken at the front of the machine, showing more particularly the arrangement of the stencil card receiver.

Fig. 3 is a plan view of the machine with the cabinet cover being cut away to more clearly show the interior parts and their operative relationship.

Fig. 4 is a sectional view taken on the line 4—4 of Fig. 3.

Fig. 5 is a sectional view taken on the line 5—5 of Fig. 3.

Fig. 6 is a sectional view showing in detail the construction of the clutch for effecting two cycles of operation of the main drive shaft and is taken on the line 6—6 of Fig. 3.

Fig. 7 is a detail view showing the ink regulating plate and its associated control parts.

Fig. 8 is a plan view of the clutch mechanism shown in Fig. 6.

Fig. 9 is a detail view of the parts employed to axially shift one of the inking rollers.

Prime mover

The power for operating the various parts of the machine is derived from a motor 20 (Fig. 3) which operates constantly so as to rotate a pulley 21 which drives a shaft 22 through a belt connection 23. The shaft 22 is the driving shaft of a speed reduction mechanism designated generally by the reference numeral 24 and the driven shaft 25 thereof (Fig. 3) rotates at a speed reduced with respect to the shaft of motor 20. Gear 26 and ratchet wheel 27 are driven by the shaft 25 of the speed reduction mechanism.

The two-revolution clutch is similar in construction to a well known form of a one-revolution clutch mechanism but is modified herein so that two successive revolutions of the main drive shaft can be effected for each machine operation. In general the clutch consists of the ratchet clutch wheel 27 which rotates constantly and also includes a clutch dog 28 (Fig. 6) which effects the driving connection to the main drive shaft, and the clutch connection between the ratchet clutch wheel 27 and the clutch dog 28 is main-

tained for two revolutions of the main drive shaft.

Referring to Fig. 8 it will be noted that the main drive shaft 29 carries a clutch arm 30 upon which is pivoted the clutch dog 28. A spring 31 interposed between the extremity of the clutch dog 28 and an extension 32 (Fig. 6) of the clutch arm 30 tends to effect the clutch engagement between the clutch dog 28 and the ratchet clutch wheel 27 but such engagement is normally prevented by the cooperation of a depending extension 33 of the clutch dog 28 with a lug 34 of a clutch release arm 35. When the clutch release arm 35 is rocked downwardly as viewed in Fig. 6, the lug 34 will be disengaged from the extension 33 of the clutch dog 28, enabling the clutch connection between the arm 30 and the clutch ratchet wheel 27 to be made by spring 31, thereby rotating the main drive shaft 29 in a counterclockwise direction (see Fig. 6). The rocking of the clutch release arm 35 to effect the clutch connection is effected by the manipulation of a bar 36 which extends in front of the machine as shown in Fig. 1 to be depressed by the operator so as to initiate the operation of the machine. The bar 36 is carried by a pair of arms 37 which are carried by a rock shaft 38 and to said rock shaft there is connected an upstanding arm 39 (Fig. 6) to which is pivoted a link 40, the free end of said link being provided with an L-shaped slot 41. A spring 42 connected to the link 40 raises the free end of the latter upwardly so that the vertical portion of the slot 41 normally engages a stud 43 carried by the vertical arm of the clutch release arm 35.

Obviously, when the bar 36 is depressed, rock shaft 38 will be rocked and through the medium of the arm 39 the link 40 will be drawn to the right as viewed in Fig. 6. Through the engagement of the bottom portion of the slot 41 with the stud 43, the clutch release arm 35 will be rocked clockwise, disengaging the lug 34 from the extension 33 of the clutch dog 28. Secured to the shaft 29 is a cam 44 and cooperating with the cam edge 45 of the cam 44 is a stud 46 secured to the link 40. When the rotation of cam 44 starts, its cam edge 45 will rock link 40 so that while stud 46 engages the circular portion 59 of cam 44, the horizontal portion of the slot 41 will cooperate with the stud 43 for a purpose to be more evident later.

As suggested before, means are provided to maintain the clutch engagement of two cycles of operation of the main drive shaft 29 and this is preferably secured as follows: The clutch release arm 35 is provided with a shoulder 47 so that when the clutch release arm 35 is rocked downwardly a spring 48 will be effective to rock a latch arm 49 so that a lug 50 of said latch arm will snap over the shoulder 47 of the clutch release arm, latching it in depressed position. Obviously, this will maintain the lug 34 in such position that it will not be contacted by the extension 33 of the clutch dog 28 so that upon one complete revolution of the shaft 29 the clutch engagement will be maintained and the shaft 29 will continue with its second revolution. Pivoted by a stud 51 on the cam plate 44 is a ratchet-shaped wheel 52 and secured to the ratchet wheel 52 is a scalloped shaped disk 53 which has four high projections 54. The scalloped disk 53 and therefore the high projections 54 are in the plane of the latch pawl 49. In the plane of the ratchet wheel 52 is a projection 55 of a stationary plate 51. When the first revolu-

tion of the shaft 29 begins, the engagement of the projection 55 with one of the teeth of the ratchet wheel 52 will rock the ratchet wheel one step clockwise, positioning the scalloped disk 53 so that none of the projections 54 will strike the extension 55 of the latch arm 49. This position of the ratchet wheel 52 and disk 53 is maintained by a detent pawl 56 of common construction and which impositively holds the ratchet wheel 52 and disk 53 in their stepped position. When the second revolution of the drive shaft 29 ensues, the extension 55 will again cooperate with the ratchet wheel 52 to rotate it another step clockwise, this time bringing one of the projections 54 in the path of the cam extension 55 of the latch arm 49. As the projection 54 strikes such extension 55 it will rock the latch arm 49, disengaging it from the shoulder 47 of the clutch release arm 35, now bringing the lug 34 in the path of the depending extension 33 of the clutch dog 28. The cooperation of the lug 34 and the extension 33 will rock the clutch dog 28 out of engagement with the clutch wheel 27, effecting the disengagement of the clutch at the termination of two revolutions of the main drive shaft 29.

It is desirable to enable the clutch arm 35 to freely rock to its normal position even if the operator keeps bar 36 depressed after the second revolution of shaft 29 has commenced and it will be evident from Fig. 6 that during the second revolution of shaft 29 the stud 46 carried by link 40 is engaged by the circular periphery 59 of the cam 44. This will position link 40 to bring the horizontal portion of the slot 41 in cooperation with the stud 43 so that even maintained pressure on the bar 36 will enable arm 35 to freely return to its normal position. In order to maintain the clutch dog in its disengaged position and to prevent rebound when the clutch disengagement is effected, the usual rebound pawl 60 is provided and the latter is pivoted upon the clutch release arm 35.

Summarizing, it is evident that upon the depression of the bar 36 the clutch engagement will be effected so that two revolutions of the main drive shaft 29 will ensue.

Means for locking the manually operated bar 36

The machine shown herein is provided for the purpose of inking an inserted stencil or if so desired printing upon a record file card from the inserted stencil. It is preferable to provide means to prevent the operation of the machine unless such record elements are inserted for inking and printing operations, otherwise the ink would be transferred to the platen in the absence of interposed record elements, thus causing the smear in the subsequent printing operation.

The stencil card 64 (Fig. 2) and record file card are inserted in a guide chute 65 (Figs. 1 and 5) between guide plates 66 and a stationary platen strip 67 which is preferably a steel plate. When these are in their proper position they will actuate a pair of locking bell cranks 68 (Figs. 3, 4 and 5) thereby withdrawing the locking arms 69 therefrom out of engagement with lugs 70 carried by arms 71 secured to the shaft 38. By the normal cooperation of the locking arms 69 and the lugs 70 it is evident that the bar 36 cannot be depressed. However, when the stencil and adjacent file card are properly inserted, the locking arms 69 are disengaged from the lugs 70 so that the shaft 38 may be rocked by the manual operation of the bar 36.

Ink distributing mechanism

The present ink distributing arrangement provides for the even distribution of the ink so that the inking and printing roller will be able to effect even impressions from the indentations in the stencil and evenly ink the same.

Referring to Fig. 8, it will be seen that the constantly rotating gear 26 drives a pinion 75 which is secured to a shaft 76. The shaft 76 is journaled in a pair of supporting frame plates 77 and 78 (Fig. 3) and secured to the constantly rotating shaft 76 is a rubber inking roller 79 (Fig. 5). This receives ink from an ink reservoir in a manner to be subsequently explained and in frictional contact with the inking roller 79 is an inking roller 80 secured to a shaft 81 which is also journaled in the side frames 77 and 78. Since the inking rollers 79 and 80 are in frictional contact at their periphery, as well as geared together by gears not shown, the ink on the periphery of roller 79 will be distributed over the roller 80 as the latter rotates. As the roller 80 rotates it will transfer the ink on its periphery to a roller 82 which is in frictional contact therewith and preferably intergeared by gears not shown. The inking roller 82 is supported on a shaft 83 also journaled in the side plates 77 and 78.

To provide for an even distribution of the ink transferred to the inking roller 82 it is preferable to move the roller 80 axially in addition to its constant rotation and this is preferably effected in the following manner. Secured to the shaft 76 is a gear 84 (Fig. 8) which meshes with a gear 85 secured to a worm 86. The worm 86 meshes with a related worm wheel 87 secured to a shaft 88. Through such drive connections the shaft 88 is driven constantly but at a very slow speed so that a cam 89 secured thereto rotates slowly (see Fig. 9). The cam 89 cooperates with flanges 90 carried by a slidably mounted plate 91. The latter as shown in Fig. 8 fits over a reduced portion 92 of the shaft 81 and by means of a collar 93 pinned to the reduced portion, the lateral movement given to the plate 91 by means of the cam 89 is transmitted to the shaft 81. Therefore, the shaft 81 also moves axially; first in one direction and then in the other, thereby causing the roller 80 to distribute the ink on the periphery thereof more evenly over the roller 82 than could be accomplished without the axial movement of the roller 80. When the ink is finally transferred to the roller 82 it is evenly distributed over the periphery thereof and this roller in turn distributes the ink on its periphery to a soft rubber roller 94 which is the roller provided for the purpose of inking the stencil and effecting the printing impression from the stencil on the record card.

The roller 94 is journaled on a shaft 95 and said shaft as shown in Figs. 4 and 5 is carried by a pair of reciprocable supporting plates 96 and 97. The supporting plates 96 and 97 are each provided with guide slots 98 and 99 cooperating with respective guide studs 100 and 101 carried by the side supporting plates 77 and 78 as the case may be. By such guide means the plates 96 and 97 are mounted for reciprocating movement and in the normal position of the parts pairs of springs 102 and 103 attached to the plates 96 and 97 move such supporting plates rearwardly so as to maintain the initial frictional contact between the inking roller 94 and its cooperating inking roller 82. Thus, in the

normal position of the parts the inking roller 94 will rotate constantly. The movement of the inking roller 94 towards the platen 67 is effected by a pair of cams 104 and 105, both of which are secured to the main drive shaft 29 and which co-operate with respective rollers 106 and 107, both of which rollers are journaled on the shaft 95. During the rotation of the drive shaft 29 the high portions of the cams 104 and 105 will contact the rollers 106 and 107 and as the cams continue to rotate, the higher portions thereof will move both of the supporting plates 96 and 97 to the right as viewed in Figs. 4 and 5. This will bring the roller 94 out of contact with the inking roller 82 and by momentum the roller 94 will continue to rotate as it approaches the platen strip 67. To provide for the stopping of the inking roller 94 so that it is stationary when the inking and printing impressions are effected, there is provided the following means: Mounted upon a stud 108 (Fig. 5) is an arm 109 provided with a lug 110 in the plane of a ratchet wheel 111 (Fig. 3), rotatable with the inking roller 94. As the inking roller 94 is moved, to the right as viewed in Fig. 4, the inking roller 94 rotates counterclockwise and in a certain forward position of the roller 94 the lug 110 will engage one of the teeth of the ratchet wheel 111, thereby stopping the rotation of the inking roller 94 and maintaining it stationary at the time that the roller 94 makes contact with the stencil card to thereby distribute the ink on the roller over the stencil paper strip and to cause the ink to be forced through the indentations on the stencil 35 paper to a record card which is against the platen strip 67. This pressure is maintained during the high portion of the cams 104 and 105, for distributing by maintained pressure contact the ink over the stencil paper.

It is preferable that the inking and recording operation be effected twice, particularly when the stencils are inked for the first time. The second inking impression is effected by the second rotation of the shaft 29 which is controlled and effected by means of the main drive clutch shown in Fig. 6 and previously described. After the first inking impression the roller 94 again makes contact with the cooperating inking roller 82 and more ink is distributed on the surface of the roller 94. This insures that even if the same peripheral portion of the roller 94 is again placed in contact with the stencil that the ink previously removed therefrom in the first inking operation will be replenished so that the stencil can again be inked and thoroughly inked when it is used the first time. The operations which are effected during the second inking are precisely the same as previously explained so that a repetition of its description appears to be unnecessary. After the second inking the main drive shaft 29 comes to rest after its second revolution and the inked stencil and file card printed can be manually removed by withdrawing them from the chute 65. Another stencil and card can be inserted in the machine and a repetition of the operations can be performed by the subsequent depression of the bar 36.

Ink reservoir

The supply of ink is carried by a detachable ink supply unit which consists of a pair of side plates 115, 116 (Figs. 4 and 5) which are connected by a cross member 118. The cross member 118 rests in a pair of bracket plates 119 and when the frame is in such position it is held by

means of a pair of latch arms 112, by means of which latch arms the unit may be attached to the machine or may be detached therefrom for the purpose of placing a new ink supply in a tank 120, also carried by the ink supply unit. Revolving in the tank 120 is a plurality of circular disks 121 which are secured to a shaft 122. The shaft 122 and therefore the disks 121 are rotated so that the latter will bring a supply of ink to a steel inking roller 123 also carried by the ink supply frame. While not shown in the drawings there is a normal separation between the periphery of the ink distributing roller 123 and the disks 121 about .003 of an inch. The ink distributing roller 123 is in frictional contact with the continuously operating roller 79 so that the latter will rotate the ink distributing roller 123 to pick up the ink from the disks 121. In order to determine the amount of ink that will remain on the disks 121 there is provided a doctor blade 124 which is adjustable towards the periphery of the disks 121 so as to determine the amount of ink which will remain on the peripheral surfaces thereof. The doctor blade 124 is adjustable in any suitable way so that it can be placed closer to the disks 121 to decrease the supply of ink fed from the tank, or to be removed from the disks so as to increase the supply of ink.

To further insure that the ink will be properly distributed to the distributing roller 123 there is located in the tank 120 an agitator which consists of a bail-shaped plate 125 which is slotted and which bail-shaped plate is immersed in the ink supply. One arm of the agitator plate 125 extends upwardly as identified by reference numeral 126 (Fig. 5) and the latter cooperates with an eccentrically mounted disk 113 secured to the shaft 76. Since the disk 113 continually rotates, it will be obvious that the uninterrupted reciprocations of the agitator blade 125 will keep the bath of ink in movement to keep its consistency uniform.

The amount of ink which is picked up by the disks 121 and conveyed to the ink distributing roller 123 is regulated by varying the extent of the step of rotation of the shaft 122 and this is especially provided for by the mechanism shown in Fig. 4. Loosely mounted on the shaft 122 is a double arm 127 and the upper arm thereof carries a spring-pressed pawl 128 which is in the plane of a ratchet wheel 129 secured to the shaft 122. Connected to the reciprocating plate 96 by means of a stud 130 is a link 131 which is provided with a slot 132 in which fits a stud 133 carried by the upper arm of the double arm 127.

In the position shown in Fig. 4, the double arm 127 is rocked the maximum amount of movement because the pin 133 engages the left end of the slot 132 so that immediately upon the movement of the plate 96 the link 131 will be drawn to the right to immediately rock the arm 127 against the tension of a spring 134 attached to the lower arm of the double arm 127. This spring 134 is effective to return the double arm to its normal position during which time the pawl 128 idly ratchets over the ratchet wheel 129.

To cause a lesser rocking movement of the shaft 122 and therefore the disks 121 so that a lesser amount of ink will be picked up by the latter there is provided a relating plate 135 which is slidably mounted by means of guide pins 136 as is viewed in Fig. 7. By positioning

the regulating plate 135 to the front of the machine at which desired position it is held by detent pawl 137, it will be seen that by the cooperation of the extension 138 of the regulating plate 135 with the upper arm of the double arm 127 the latter will be positioned so that the pin 133 occupies an intermediate position with regard to the slot 132. Therefore, a certain amount of lost motion is provided between the left end of the slot 132 and the stud 133 and while the link 131 is given an invariable movement a smaller amount of movement is given to the double arm 127 regulated by the position of the regulating plate 135. For the adjustment of the plate 135 the latter is provided with an upwardly extending pin 139 which is manually adjustable by the operator and positioned along a scale 140 (Fig. 1). The scale position of the pin 139 determines the extent of movement given to the double arm 127 and the scale index is so provided that the operator will know at the particular position of the pin 139 the amount of ink which is conveyed from the ink supply unit to the distributing rollers in the manner previously described.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a stencil inking machine, the combination of a main drive shaft, a constantly rotating driving shaft, a clutch device interposed between said shafts and provided with means to enable the rotation of the main drive shaft, a series of peripheral contacting inking rollers driven constantly by said main drive shaft, a reciprocable pressure inking roller in frictional peripheral contact with the last inking roller driven to provide the sole driving means for the pressure roller, means for reciprocably carrying said pressure roller, a stationary stencil platen against which said pressure inking roller presses an interposed stencil, and cam means driven by the main drive shaft for effecting the reciprocation of said pressure roller carrying means to shift the pressure roller out of frictional contact with said last inking roller to enable the pressure roller to come to rest and contact the stencil and press it against the platen to ink the stencil, and to enable the return of said pressure roller out of contact with the stencil to then frictionally contact with the last driven inking roller to be frictionally driven thereby for re-inking of the pressure roller.

2. In a stencil inking machine, the combination of a main drive shaft, a constantly rotating driving shaft, a clutch device interposed between said shafts to effect their clutch engagement and provided with means to enable the rotation of the main drive shaft, a series of peripheral contacting inking rollers driven constantly by said main drive shaft, a reciprocable pressure inking roller in frictional peripheral contact with the last inking roller driven to provide the sole driving means for the pressure roller, means for reciprocably carrying said pressure roller, a stationary stencil platen against which said pres-

sure inking roller presses an interposed stencil, cam means driven by the main drive shaft for effecting the reciprocation of said pressure roller carrying means to shift the pressure roller out of contact with said last driven inking roller to enable it to come to rest and contact the stencil and press it against the platen to ink the stencil and to enable the return of said pressure roller out of contact with the stencil to then frictionally contact with the last driven inking roller to be frictionally driven thereby for re-inking of the pressure roller, a manually operated means manually operated after a stencil has been interposed between the platen and said pressure roller, and means operated by said manually operated means to effect the engagement of said clutch device.

3. In a stencil inking machine, the combination of a main drive shaft, a constantly rotating driving shaft, a clutch device interposed between said shaft and provided with means to enable the rotation of the main drive shaft, a series of peripheral contacting inking rollers driven constantly by said drive shaft, a reciprocable pressure inking roller in frictional peripheral contact with the last inking roller driven to provide the sole driving means for the pressure roller, a ratchet-shaped wheel carried by said pressure roller, means for reciprocably carrying said pressure roller, a stationary stencil platen against which said pressure inking roller presses an interposed stencil, a stop arm, and cam means driven by the main drive shaft for effecting the reciprocation of said pressure roller carrying means to shift the pressure roller out of contact with said last driven inking roller to enable the pressure roller to be stopped in its rotation and then to contact the stencil and press it against the platen to ink the stencil and to cause said ratchet wheel to be engaged by said stop arm to stop the rotation of the pressure roller, and to return said pressure roller to contact the last driven inking roller to be frictionally driven thereby for re-inking of the pressure roller, and likewise disengage said ratchet wheel from said stop arm to enable the free rotation of the pressure roller by said last driven inking roller for re-inking thereof by the last driven inking roller.

4. In a stencil inking machine, the combination of a main drive shaft, a constantly rotating driving shaft, a clutch device interposed between said shaft and provided with means to

enable a rotation of the main drive shaft, a series of peripheral inking rollers driven constantly by said drive shaft, a reciprocable pressure inking roller in frictional peripheral contact with the last inking roller driven to provide the sole driving means for the pressure roller, means comprising frame plates carrying the shaft of said pressure roller for reciprocably carrying said pressure roller, a stationary stencil printing platen against which said pressure inking roller presses an interposed stencil, and a plurality of cam means driven by the main drive shaft, each engaging the ends of said pressure roller shaft for effecting the reciprocation of said pressure roller carrying plates to shift the pressure roller out of frictional contact with said last driven inking roller to enable the pressure roller to come to rest and contact the stencil and press it against the platen to ink the stencil and to return said pressure roller after the stencil inking operation to contact the last driven inking roller to be frictionally driven thereby for re-inking of the pressure roller.

5. A stencil inking machine comprising a main drive shaft, a driving shaft, means to initiate and effect the rotation of said drive shaft by said driving shaft a series of inking rollers in serial peripheral contact, a pressure roller in immediate peripheral contact with the last driven inking roller of said series providing the sole driving means for the pressure roller, means to carry a supply of ink, a distributing inking roller in peripheral contact with the first driven inking roller of said series, rotatable means within said ink carrying means to convey ink to said distributing inking roller, means operated by said drive shaft to effect a predetermined extent of rotation of said rotatable means, a platen strip against which a stencil is placed to be contacted by said pressure roller, and cam means driven by said main drive to effect a reciprocation of said pressure roller, to effect in said reciprocation the forward movement of said pressure roller out of contact with the last driven inking roller to enable it to come to rest and then in contact with said stencil, and the return of said pressure roller in peripheral contact with the last driven roller to be frictionally driven thereby for re-inking of the pressure roller prior to the next inking contact with the stencil.

ALBERT W. MILLS.
FRANK J. FURMAN.
